CONCEALED HINGE

Joseph Soss, Roselle, N. J.

Application August 5, 1937, Serial No. 157,483

2 Claims. (Cl. 16—164)

This invention relates to concealed hinges and particularly devices of this class designed for use upon inner surfaces of stationary and swinging supports with the attaching plate portions arranged in a plane of the longitudinal plane of the supports when the hinge is in closed position, and the object of the invention is to provide a hinge of the class described employing butt members having flat attaching plate portions constituting the outer surface of the hinge, and link supporting bearings extending rearwardly from the central parts of the attaching plate portions to provide a relatively thin and compact arrangement of butts and links; a further object being to provide a hinge of the character described wherein two pairs of similar links are arranged in interfitting relation, the separate pairs of links being fixedly pivoted at one end to the respective butts and movably coupled at their other ends to the opposed butts, the pairs of links being pivoted together centrally thereof in such manner as to dispose the pivot intermediate the bearing portions of the respective butts when the hinge is in closed position; a still further object being to provide a hinge of the character described wherein the separate butts are preferably composed of die castings whereby a simple and economical hinge structure is provided; a further object being to provide a hinge of the character described wherein the complete hinge is formed from actually two parts aside from the pintle pins employed, the parts being simply duplicated, and with these and other objects in view the invention consists in a hinge of the class and for the purpose specified which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a rear view of the hinge in closed position.

Fig. 2 is a side edge view thereof.

Fig. 3 is a front view of the hinge in closed position.

Fig. 4 is a plan view of the hinge showing the manner of attaching the same to independent supports.

Fig. 5 is a transverse section through the hinge, the section being substantially on the line 5—5

of Fig. 3 and showing the hinge attached to its supports.

Fig. 6 is a view similar to Fig. 5 showing the hinge in open position.

Fig. 7 is a face view of the hinge as shown in Fig. 6, and

Fig. 8 is a view similar to Fig. 5 showing a slight modification.

In the construction shown, the hinge consists of two butts 10, 10a which are of similar construction, each butt having a relatively long flat plate-like outer surface 11 which is apertured at its ends as seen at 12 to provide what may be termed attaching plate portions 13 at the ends of the butts. The butts have central recesses 14 which are disposed on adjacent edges of the butts when the hinge is in closed position, which recesses open through the outer surfaces of said butts. One end wall of each recess is grooved as seen at 15, and these grooves are disposed one at 20 the top, and the other at the bottom of the hinge in the assemblage of the parts, as will be seen. These grooves provide free relative movement of the links of the butts.

At the rear surfaces of the plates 11 are inwardly projecting arc-shaped bearing portions 16 arranged with their opposed surfaces 17 in substantial alignment with the recesses 14. The surfaces 17 of the bearings 16 are provided with angularly arranged grooves 18 opening outwardly 30 through the outer sides of the bearings, as seen at 19 in Fig. 5 of the drawing. The body portion 20 of the butts joining the bearings 16, are somewhat thicker in parts than the thickness of the attaching plate portions 13.

I also employ two pairs of similarly formed links 21, 21a each pair of links consisting, in the construction shown, of two laminated links 22 and three laminated links 23, as will clearly appear upon a consideration of Fig. 1 of the drawing. However, each link is of the same construction and consists of a curved member of the contour clearly shown in Figs. 5 and 6 of the drawing, having an enlarged pintle bearing 25 at one end, an offset and enlarged pintle bearing 26 at the other end, and a centrally or substantially centrally enlarged bearing 27.

The bearings 25 of the pair of links 21 is fixedly pivoted to the butt 10 on a pin 28, whereas the bearings 25 of the pairs of links 21a are fixedly 50 pivoted to the butt 10a on the pin 29. The pins 28 and 29 are arranged in apertures 30 and 31 respectively, extending through the plates 11. Mounted in the bearings 26 of the pairs of links 21 is a pin 32 which slides in the grooves 18 55

of the butt 10a, and a pin 33 is mounted in the bearing 26 of the pairs of links 21a and operates in the grooves 18 of the butt 10. The respective pairs of links 21, 21a are pivoted together at the bearing 27 by pin 34.

From the foregoing it will appear that the complete hinge is made from a single butt part 10, 10a and from a single link which is used in multiples to make up the pairs of links 21, 21a plus the use of the pintle pins employed. It will therefore be seen that a very economical hinge structure is provided.

In Figs. 4, 5 and 6, the butts 10, 10a are shown mounted in connection with supports 35 and 36 respectively. The support 35 constitutes the swinging member and the support 36 the stationary support. In the construction shown, these supports are in the form of sheet metal plates, and rivets 37 are employed, note Fig. 4, for securing the butts in position. However, any type of fastening may be provided. It will be understood that the butts may be mortised in recesses formed in the inner surfaces of the supports in the usual manner, depending entirely upon the construction of the supports.

In the construction shown, the hinge is designed to swing through an arc of 180° so as to bring the two supports 35 and 36, which are normally in one alignment, into parallel relation to each other, as is indicated in Fig. 6 of the drawing. In this connection it will be apparent that the spacing between the butts may be varied by the linkage to suit supports of different thicknesses, while at the same time bringing adjacent edges of the supports in close proximity to each other, as is indicated at 38 in Fig. 4 of the drawing. It will also appear that the links are recessed at opposite sides of the central bearings 27 as indicated at 39, note Fig. 6, to clear the protruding adjacent edges of the supports 35 and 36 when the hinge is moved into open position.

The bottom surface 17 of the bearing 16 of the butt 10 is recessed to form a stop shoulder 40. A similar shoulder 40a is formed on the upper surface 17 of the upper bearing 16 of the butt 10a against which the links 22, fixedly pivoted to the butts 10, 10a, strike in limiting the closing movement of the hinge. The engagement with the shoulder 40 is clearly seen in Fig. 5 of the drawing, which shoulder is arranged diagonally as will appear. The opening movement of the hinge is limited by the inner ends of the grooves 18, as will be apparent.

The hinge of the character described is comparatively thin in thickness, that is to say, the distance between the front face 11 and the back of the hinge. This thickness may be varied by using different linkage and otherwise modifying the structure of the hinge. It will also be noted that by virtue of the linkage employed, the hinge can be mortised within the boundaries of the depth or thickness of the hinge, as the links do not swing inwardly beyond the position shown in Figs. 4 and 5, in the operation of moving the hinge into open position.

When the hinge is in closed position it will appear that the overlapped pairs of links form a substantially solid supporting wall between opposed surfaces 17 of the bearing 16 adjacent the pivot 34, as will appear from a consideration of Fig. 1 of the drawing, whereas a similar support is provided between the pairs of links when the hinge is in open position, as seen in Fig. 7 of the drawing. The combined laminated links

form a curved solid arch between the adjacent surfaces 17 of both butts. These structural features will produce a very strong and durable hinge by reason of the fact that the solid wall structure is maintained substantially at all times throughout the swinging movement of the hinge, thereby producing the effect of a solid link between the two butt parts in the several positions thereof.

In the construction shown in Fig. 8 I have illustrated two butts 41, 41a different from the butts 10, 10a simply in the provision of wider bearing portions 42, and by modifying the shape of the pairs of links 43, 43a so that said pairs of links will be completely housed within the bearings 42 of the butts 41, 41a as will be apparent. With this construction, the pairs of links 43 are pivoted to the butt 41 as at 44 and movably coupled with the butt 41a as at 45, whereas the links 43a are fixedly pivoted to the butt 41a as at 46 and movably coupled with the butt 41 as at 47, the same as in the structure shown in the other figures, the two pairs of links being pivotally coupled centrally thereof as at 48.

It will of course be understood that other shapes and forms of links and butts may be employed as well as a different arrangement or manner of mounting the respective butts may be provided in different uses of the hinge.

Having fully described my invention, what I claim as new and desire to secure by Letters Patent, is:

1. A hinge for attachment to inner surfaces of thin sheet-like supports arranged in edge to edge relation, said hinge comprising two butts having continuous outer elongated portions terminating at upper and lower ends in integral attaching plate portions, the outer surfaces of said body portions, including the attaching plate portions thereof, being arranged in a common plane and with adjacent edges of the attaching plate portions in edge to edge relation when the hinge is in closed position, said outer surfaces of the butts being arranged upon and secured to the inner surfaces of sheet-like supports, spaced bearings projecting from the inner surfaces of said body portions and forming, in conjunction with said body portions, U-shaped portions, the channels of which open through the rear and sides of the butts and partially through the front surfaces of said butts at adjacent edges thereof, and a link unit comprising links pivoted and slidably movable in each butt and pivoted together for hingedly coupling said butts.

2. A concealed hinge for attachment to the inner surfaces of relatively thin supports at adjacent edges of said supports, said hinge comprising substantially similar butts, each comprising a long member having a flat outer surface and a U-shaped link supporting portion projecting at the opposed inner surface thereof; and the ends of said member forming attaching plate portions of said butts, the attaching plate portions being in edge-to-edge relation to each other with the outer surfaces of the attaching plate portions arranged in a common plane when the hinge is in closed position, said outer surfaces lying flatly upon and secured to the inner surfaces of the thin supports at adjacent edges of said supports, and a linkage coupled with said U-shaped portions for hingedly coupling said butts.

JOSEPH SOSS.
